UNITED STATES PATENT OFFICE.

JOHN MAHER, OF BAY CITY, MICHIGAN.

WATER-TUBE BOILER.

SPECIFICATION forming part of Letters Patent No. 544,316, dated August 13, 1895.

Application filed April 20, 1894. Serial No. 508,348. (No model.)

To all whom it may concern:

Be it known that I, JOHN MAHER, a citizen of the United States, residing at Bay City, county of Bay, State of Michigan, have invented new and useful Improvements in Water-Tube Boilers, of which the following is a specification.

My invention relates to an improvement in steam-boilers, and it pertains more especially to the smoke-box of combined water-tube and fire-tube boilers; and it consists in the arrangement and construction of the parts with the object of providing a smoke-box that can be attached to a combined water-tube and fire-tube boiler that will greatly increase the heating-surface and at the same time provide more efficient means for water circulation.

In the accompanying drawings, Figure 1 is a front elevation of the boiler with a portion of the front broken away for the purpose of showing the arrangement of the water-tubes. Fig. 2 is a longitudinal central section of the invention taken upon the line A B, Fig. 1. Fig. 3 represents a rear perspective view of the invention.

Referring to letters, A represents the cylindrical shell of the fire-tube portion of the boiler, and B is the steam-dome secured to the shell A by means of rivets, (shown at C.) D is the front head of the shell A, and E is the rear head of the same, and F is the fire-tubes. The heads D and E are connected by the said fire-tubes F, which form the fire-tube portion of the boiler.

G represents a manhole provided in the upper portion of the rear head E for the purpose of a person entering the shell A for cleaning or other desirous purposes.

H is the front water-leg, made rectangular in form and the full width of the shell A, and I is its water-space within, and J represents the rear water-leg, and D' is the smoke-box formed by the said leg J. K is its water-space within. The rear leg J is also made rectangular in form and the full width of the shell A.

L represents an opening formed in the rear head E above the fire-tubes F and below the water-line C for the purpose of connecting the rear water-leg J by means of rivets represented at O, and a right-angle bend at R, projecting horizontally far enough to provide

suitable space for the smoke-box D', thence projecting down to M, where the outer sheet of the said leg J is, and riveted to an angle-iron J', which forms the support for the said water-leg J, whereby a large and efficient opening is procured in the shell A at L for the purpose of increasing water circulation, and at the same time the right-angle bend 60 formed in the upper end of the water-leg J from R to L greatly increases the heating-surface.

N represents a pipe secured to an opening formed in the lower portion of the boiler-shell A at E', and secured thereto by means of rivets, (shown at P.) The opposite end of the said pipe N is secured to the rear water-leg J, and has exit therein by means of an opening formed at F' in the said water-leg J and secured thereto by means of rivets, as shown at Q, for the purpose of providing additional water circulation and providing means for the sediment to have exit to the rear water-leg J, where it is removed by means of a hand-hole, (shown at O'), and at the same time the said pipe N provides the lower support for the circular shell A. The front water-leg H is secured to the shell A by means of rivets (shown at S) and projects downward to T, where its outer sheet projects below the said water-leg H, and is riveted to an angle-iron K', which forms the support for the said water-leg H. The said water-leg H also has a hand-hole provided in its lower 85 portion at L' for the purpose of removing sediment accumulated therein.

U represents the water-tubes placed on an incline with their front ends elevated and connected to the inner sheets of the water-legs J and H.

G' are the grates, and H' the apron, while I' is the fire-box door.

M' is the fire-box. The said fire-box M' and the water-tubes U are inclosed at the sides by 95 the asbestos walls shown at N' N'.

W and V represent plugs provided in the outer plates of the front and rear water-legs J and H for the purpose of removal, with the object of removing or repairing the water-tubes U.

What I claim, and desire to secure by Letters Patent, is—

In a combined water tube and fire tube

boiler of a cylindrical shell having circular heads, fire tubes, connecting the said heads in combination with the front and rear water legs made rectangular in form and extending
5 the full width of the said cylindrical shell, the rear circular boiler head provided with an opening between the water line and the flues, the full width of the said head, the right angle bend formed on the upper end of the
10 rear water leg and secured to the said open-

ing formed in the said rear circular head, and the smoke box provided by the rear water leg and its right angle bend, substantially as described.

In testimony whereof I hereunto affix my 15
signature in the presence of two witnesses.

JOHN MAHER.

Witnesses:

G. R. MONCKS,
L. M. SANDERS.
